UNITED STATES PATENT OFFICE.

JOHN H. GAVIN, OF CHICAGO, ILLINOIS, ASSIGNOR TO L. WOLFF MANUFACTURING COMPANY, OF CHICAGO, ILLINOIS, A CORPORATION OF ILLINOIS.

DESIGN FOR A LAVATORY.

41,841.

Specification for Design.

Patented Oct. 10, 1911.

Application filed December 5, 1910. Serial No. 595,790. Term of patent 14 years.

To all whom it may concern:

Be it known that I, JOHN H. GAVIN, of the city of Chicago, in the county of Cook, in the State of Illinois, have invented a new, original, and ornamental Design for Lavatories, of which the following is a specification, reference being had to the accompanying drawing, forming a part thereof.

The figure is a perspective view of a lavatory showing my new design.

I claim:

The ornamental design for a lavatory, as shown.

JOHN H. GAVIN.
